PROCESS FOR HEAT TRANSMISSION

Ludwig Rosenstein, San Francisco, Calif., assignor to Shell Development Company, San Francisco, Calif., a corporation of Delaware

No Drawing. Application July 31, 1933, Serial No. 683,014

15 Claims. (Cl. 252—5)

The present invention is concerned with heating fluids for high temperature work such as used for indirect heating, power cycles and the like.

This method is useful in the art of distillation or evaporation of liquids and is particularly applicable when the distillation or evaporation is to be carried out at high temperatures and under subatmospheric pressure. It finds specific usage in the distillation of mineral oils for the manufacture of lubricants.

The present invention provides for the utilization of a class of compounds as heat transmitting material which are generally able to resist high temperatures without decomposing, and which can be used at ordinary or slightly raised pressures, which makes it possible to use simplified apparatus.

The substances as a class are compounds of relatively low volatility and of comparatively high boiling point as well as inert and stable.

When the operating temperature is above that at which the heating agent is fairly stable, it may be desirable to stabilize the agent or agents by incorporating with it or them a substance capable of overcoming any decomposition tendency, preferably a substance of higher boiling temperature which will by mass action or otherwise restrict or obviate any decomposition reaction, especially during prolonged heating.

The heat transfer medium may be compounded with certain substances to modify its tendency to solidify at relatively low temperatures. Substances as p-hydroxy diphenyl, pyrene, and naphthalene or their mixtures are useful. Besides the modifying agents, the heat transfer medium may have incorporated therewith one or more stabilizing substances as described heretofore.

My heat transfer medium, which may or may not have one or more of the above-mentioned auxiliary agents incorporated therewith, may, if desired, be employed in conjunction with one or more of the conventional heat transfer mediums as diphenyl, diphenyl oxide, diphenyl methane, di-diphenyl oxides or ethers, and the like.

My invention comprises the utilization as heat transfer medium, of secondary alkyl esters of polycarboxylic acids which acids may be of aliphatic, aromatic or aralkyl character and may or may not be further substituted. Unsaturated as well as saturated polycarboxylic acids may be used and they may be either di-, tri-, tetracarboxylic acids and the like. Their acid- as well as their neutral esters may be utilized and two or more different alkyl radicals may be on the different carboxylic acid groups so long as there

is present at least one secondary alkyl radical. I include also the symmetrical neutral esters as well as asymmetrical esters which contain different secondary alkyl radicals on the carboxyl groups.

As illustrative of the various compounds which may be utilized due to their high-boiling temperatures, may be mentioned the isopropyl, secondary butyl, secondary amyl, secondary hexyl, and higher secondary alkyl esters of phthalic acid, terephthalic acid, methyl-phthalic acid, iso-phthalic acid, citric acid, maleic acid, malic acid, tartaric acid, succinic acid, phenyl-succinic acid, trimesic acid, pimelic acid, glutaric acid, methyl malonic acid, malonic acid benzyl-malonic acid, sebatic acid, pyromucic acid, itaconic acid, aconitic acid, fumaric acid, and the like, as well as their homologues, analogues and substitution products.

Particularly suitable are the neutral esters as the diisopropyl, secondary dibutyl, secondary diamyl, secondary dihexyl phthalates and their homologues as well as those of a mixed character as secondary butyl methyl phthalate, secondary amyl ethyl phthalate, secondary butyl ethyl phthalate, isopropyl methyl phthalate, isopropyl secondary butyl phthalate.

While I have in the foregoing described in some detail the preferred embodiment of my invention and some variants thereof, it will be understood that this is only for the purpose of making the invention more clear and that the invention is not to be regarded as limited to the details of operation described, nor is it dependent upon the soundness or accuracy of the theories which I have advanced as to the advantageous results attained. On the other hand, the invention is to be regarded as limited only by the terms of the claims, in which it is my intention to claim all novelty inherent therein as broadly as is possible in view of the prior art.

I claim as my invention:

1. In a process for transmitting heat to fluids in indirect contact with heat transmitting material, the step of employing a secondary alkyl ester of a polycarboxylic acid of relatively high-boiling temperature as the heat transmitting material.

2. In a process for transmitting heat to fluids in indirect contact with heat transmitting material, the step of employing a secondary alkyl ester of an aromatic polycarboxylic acid as the heat transmitting material.

3. In a process for transmitting heat to fluids in indirect contact with heat transmitting ma-

- terial, the step of employing a poly-isopropyl ester of an aromatic polycarboxylic acid as the heat transmitting material.
4. In a process for transmitting heat to fluids in indirect contact with heat transmitting material, the step of employing a secondary polybutyl ester of an aromatic polycarboxylic acid as the heat transmitting material.
5. In a process for transmitting heat to fluids in indirect contact with heat transmitting material, the step of employing a secondary polyamyl ester of an aromatic polycarboxylic acid as the heat transmitting material.
6. In a process for transmitting heat to fluids in indirect contact with heat transmitting material, the step of employing a secondary alkyl ester of a dicarboxylic acid of relatively high-boiling temperature as the heat transmitting material.
7. In a process for transmitting heat to fluids in indirect contact with heat transmitting material, the step of employing an isopropyl ester of phthalic acid as the heat transmitting material.
8. In a process for transmitting heat to fluids in indirect contact with heat transmitting material, the step of employing a secondary butyl ester of a phthalic acid as the heat transmitting material.
9. In a process for transmitting heat to fluids in indirect contact with heat transmitting material, the step of employing a secondary alkyl ester of a phthalic acid as the heat transmitting material.
10. In a process for transmitting heat to fluids in indirect contact with heat transmitting material, the step of employing a secondary dialkyl ester of a phthalic acid as the heat transmitting material.
11. In a process for transmitting heat to fluids in indirect contact with heat transmitting material, the step of employing a diisopropyl phthalate as the heat transmitting material.
12. In a process for transmitting heat to fluids in indirect contact with heat transmitting material, the step of employing a secondary dibutyl phthalate as the heat transmitting material.
13. In a process for transmitting heat to fluids in indirect contact with heat transmitting material, the step of employing a secondary diamyl phthalate as the heat transmitting material.
14. In a process for transmitting heat to fluids in indirect contact with heat transmitting material, the step of employing a secondary alkyl ester of a polycarboxylic acid of relatively high-boiling temperature as the heat transmitting material, in conjunction with a stabilizing agent which is effective at relatively high temperatures to stabilize the heat transmitting material against decomposition.
15. In a process for transmitting heat to fluids in indirect contact with heat transmitting material, the step of employing a secondary alkyl ester of a polycarboxylic acid of relatively high-boiling temperature as the heat transmitting material, in conjunction with a modifying compound which reduces its solidifying temperature.

LUDWIG ROSENSTEIN.
